UNITED STATES PATENT OFFICE.

JAMES ALLEN HUGGINS, OF RED SPRINGS, NORTH CAROLINA.

SUBSOIL-PLOW.

1,074,176.

Specification of Letters Patent. Patented Sept. 30, 1913.

Application filed August 2, 1912. Serial No. 712,936.

To all whom it may concern:

Be it known that I, JAMES ALLEN HUGGINS, a citizen of the United States, residing at Red Springs, in the county of Robeson 5 and State of North Carolina, have invented certain new and useful Improvements in Subsoil-Plows; and I do declare the following to be a full, clear, and exact description of the invention, such as will enable others 10 skilled in the art to which it appertains to make and use the same.

This invention relates to plows, and more especially to subsoilers; and the object of the same is to produce an improved device 15 for attaching the subsoil standard to the main plow so as to permit it to swing from side to side or to be adjusted vertically.

A further object is to improve the construction of the main plow beam in order 20 to adapt it for use in connection with this attachment.

Further objects and advantages will appear from the following specification and claims, taken in connection with the accompanying drawings, wherein—

Figure 1 is a side elevation of a complete plow embodying my improvement, parts being broken away; Fig. 2 is a horizontal section on the line 2—2 of Fig. 1, omitting 30 all parts of the main plow but its beam. Fig. 3 is a vertical section of Fig. 1. Fig. 4 is an enlarged perspective detail of the inner end of the main beam and the supplemental beam, and the clevis connected 35 thereto.

No claim will be made in this application for the main plow beam B carrying the plow point P, for the main handles H for the inclined braces I connected to said handle and 40 pivoted at 2 to the beam at B, nor for the subsoil plow point S which of course may be of any approved construction as also can the main plow point P.

When my attachment is applied to a plow 45 of substantially the construction roughly indicated in the drawings, either at the time said plow is built or later, I preferably employ a supplemental beam 1 bolted or otherwise connected to the main beam B. Pivoted at 3 to the lower end of this supplemental beam is the front end of the subsoil tongue, said front end herein shown as consisting of a clevis member 4 hingedly connected as at 5 with a second member 6, 50 this member being shown in Fig. 3 as consisting of parallel side bars spaced apart by

blocks 7 at their front ends, having wear plates 8 riveted as at 9 within their rear ends, and the latter may be turned upward, backward at an angle, or preferably downward into hooks 10 as shown in Fig. 2. Between the bills of said hooks on a cross bolt 11 is mounted an anti-friction roller 12; and between said side bars forward of the wear plates 8 on another cross bolt 13 is mounted 60 a second anti-friction roller 14, the support for which is by preference a sleeve surrounding said bolt between the side bars of the member 6 so as to hold them properly spaced at this time. The function of these 65 anti-friction rollers will be set forth below.

The carriage forming a part of my improved attachment consists of duplicate spaced and substantially upright members 20 of strap iron whose lower ends are connected by a cross bolt 21 on which is mounted the shoe, herein shown as a wheel 22, and whose upper ends extend thence forward as at 23, and thence downward as at 24 to the cross bolt 13, upon which they are 70 mounted inside the side bars or members 6 of the tongue and against the opposite ends of the sleeve 15 so as to hold the front ends 75 properly spaced. Such ends are provided with parallel upright slots 25 for a 80 purpose yet to appear. The upright members 20 are connected by any suitable means such as the rivets 26 with the rear ends of the members 6 of the tongue, and thus the carriage is rigidly connected with the rear 85 end of the tongue at a slight obtuse angle 90 thereto as best seen in Fig. 1, and is supported by the shoe or wheel 22 within the furrow F which has just been formed by the main plow or upon the surface of the 95 ground if the main plow P is being dragged over the same, while the tongue is drawn forward by its connection at 3 with the offset or beam 1 and the draft is communicated through the hinge 5 and members 6 100 to said carriage.

The subsoil plow standard to which the subsoil point S is attached in any suitable manner comprises an upright member 30 passing loosely between the wear plates 8 105 and between the adjacent edges of the two rollers 12 and 14, and having its upper end turned forward as at 31 and projected between the two downturned front ends 24 of the members of the carriage as seen in Fig. 110 3. Here said front end carries a cross bolt 32 which extends through the guide slots 25,

and outside the latter the ends of this bolt are connected with twin links 33, which lead upward astride the carriage, are turned inward at their upper ends as at 34, and are pivotally connected as at 35 with a hand lever 36, which latter in turn is pivotally mounted as at 37 to the upper rear corner of the carriage. The numeral 38 designates a toothed segment supported by said carriage, and 39 is a spring latch engaging this segment and mounted upon the hand lever 36 and operated by a thumb lever 40 in the usual manner.

With this construction of parts, when the hand lever 36 is thrown forward as seen in Fig. 1 the links 33 move the cross bolt 32 downward within the guide slots 25, and the entire subsoil standard with its point S is depressed, the upright member 30 of the standard moving downward between the anti-friction rollers 12 and 14 and the wear plates 8 in a manner which will be clear. Thereafter forward movement of the main plow P cuts the furrow F, while the subsoil plow S cuts still deeper into the earth as indicated in this view. When now the depth to which the subsoil plow S will cut is to be adjusted, the operator manipulates the thumb lever 40 to disengage the latch 39 from the toothed segment 38, and then swings the hand lever 36 so that the twin links 33 adjust the position of the standard and the subsoil plow point as desired. When subsoiling is not to be done, the hand lever 36 can be thrown so far to the rear that the point S will rise above the bottom of the furrow F. When the entire plow is to be drawn over the surface of the earth, the subsoiler will be adjusted to such position that its point S will be above the bottom of the main point P, and this position of parts will ordinarily be assumed at the end of the furrow or when the plow is turned around quickly. In this action the tongue members 6 will swing to one side as the upright hinge 5 permits, and in order that the entire attachment may not interfere with the main handles H, I preferably make use of a bail which may well be a piece of stout wire or metal rod 50 connected at its extremities with said handles H as at the points 51 where the inclined braces 1 connect with the handles, and its center 52 passing loosely under the upper ends 23 of the carriage members as indicated in Fig. 1. Without further illustration than contained in this view, it will be obvious that when this detail is employed and the plow is turned suddenly about as at the end of a furrow, the side movement of the entire attachment will be permitted as the length of the bail allows, and yet the parts cannot get out of place but the attachment will trail behind the main plow and resume its proper position as soon as the operator has

turned the machine around and progressed for a short distance along his new course. The bail comes ordinarily into active use however, when the handles H are raised abnormally high or swung to one side without disengaging the subsoil point by the hand lever 36; and then the bail acts as a safeguard.

I do not wish to be confined to the use of the bail, nor particularly to any of the details hereinbefore set forth, further than as embraced in the appended claims; and it is obvious that the sizes, shapes, proportions and materials of parts can be altered at will without departing from the spirit of the invention.

By arranging the sub-soil plow and connecting the same to the main plow as herein shown and described, the subsoil plow will travel in the furrow formed by the point of the main plow and will loosen up the subsoil in the bottom of the furrow without turning said soil, thereby materially facilitating the cultivation of the soil.

While the invention is herein shown and described as an attachment for plows, it is obvious that the same may be employed as a subsoil plow in connection with any form of regular plow to which it can be attached.

What I claim as new is:

1. In a plow, the combination with the beam, point, handles, and braces; of a subsoiler and its standard, a tongue connected with said standard and with the beam and having a hinge within its length, and a bail connecting said handles and loosely engaging the subsoiler to permit the latter to swing from side to side.

2. The combination with a main plow structure including the beam, point, handles, and braces; of a subsoiler attachment comprising a carriage mounted on a shoe, a tongue connected with the carriage and pivotally connected with said beam, a hinge within the length of the tongue for permitting the carriage to swing from side to side, the subsoil point and standard, means for adjusting the standard vertically within said carriage, and a bail connecting said handles and loosely engaging through the carriage, for the purpose set forth.

3. The combination with a main plow structure including the beam, point, handles, and braces; of a subsoiler attachment comprising an upright carriage mounted on a shoe, flexible connections between said carriage and the lower end of the beam, a subsoil point and its standard, means for adjusting the latter vertically within said carriage, and a bail connecting said handles and passing loosely through the carriage, for the purpose set forth.

4. A subsoiler attachment for plows comprising a tongue consisting of a front member adapted to be connected at its front end

with the plow beam, a rear member made in spaced parallel parts having blocks between their front ends, and a hinge connecting said members and whose pintle is upright; a carriage secured to said rear member and having upright guides, the subsoil plow point, its standard moving between the parts of said rear member and its upper end turned forward and moving within said guides, and

10 means for adjusting it vertically.

5. A subsoiler attachment for plows comprising a tongue consisting of a front member adapted to be mounted on a horizontal pivot at its front end connecting it with the plow beam, a rear member made in spaced parallel parts having downturned rear ends, blocks between their front ends, and a hinge whose front leaf is connected with said front member and its rear leaf with said rear member and whose pintle is upright; a substantially upright carriage secured between the rear ends of said rear member and having upright guides, the subsoil plow point, its standard moving between the parts of said rear member and within said guides of the carriage, and means for adjusting it vertically.

6. A subsoiler attachment for plows comprising a tongue consisting of a front member adapted to be mounted on a horizontal pivot at its front end connecting it with the plow beam, a rear member made in spaced parallel parts having hooks at their rear ends, blocks between their front ends, and a hinge whose front leaf is connected with said front member and its rear leaf with said rear member and whose pintle is upright; a carriage secured between the hooked ends of said parts and having a shoe, the subsoil plow point, its standard extending between said parts, anti-friction rollers journaled between said parts in front and in rear of said standard, and means for adjusting the latter vertically with respect to said carriage.

7. A subsoiler attachment for plows comprising a tongue consisting of a front member adapted to be mounted on a horizontal pivot at its front end connecting it with the plow beam, a rear member made in spaced parallel parts having downturned rear ends, blocks between their front ends, and a hinge whose front leaf is connected with said front member and its rear leaf with

said rear member and whose pintle is upright; a carriage secured between the rear ends of said parts and having a shoe, the subsoil point, its standard extending between said parts, anti-friction rollers journaled between said parts in front and in rear of said standard, guides carried by said carriage and in which said standard moves, an adjusting lever pivoted on said carriage, and connections between said lever and standard.

8. A subsoiler attachment for plows comprising a tongue adapted to be connected at its front end with the plow beam, a carriage secured to the rear end of said tongue and comprising parallel upright members whose upper ends are extended forward and thence downward and whose downturned ends are provided with parallel guide slots, a subsoil plow point, its standard rising between the front and rear ends of said carriage and turned forward at its upper end, a cross bolt through said end and slidably mounted in said slots, a lever pivoted on said carriage, and links connecting the lever with the extremities of said bolt.

9. A subsoiler attachment for plows comprising a tongue pivotally connected at its front end with the plow beam and having its rear end formed in two spaced members, a carriage of inverted U-shape in side elevation and made in spaced members whose arms are secured between the members of said tongue, the front arms having guides, a wheel journaled between the lower ends of the rear arms, guides mounted between the arms of said tongue, the subsoil point, the subsoil standard rising therefrom between the guides of the tongue and between the front and rear arms of the carriage and turned forward between the two front arms of said carriage, means connecting the forward-turned portion of the standard with said guides, a toothed segment carried by the carriage, a lever pivoted to said carriage and having a latch engaging said segment, and a link connecting said lever with the standard.

In testimony whereof I have hereunto set my hand in presence of two subscribing witnesses.

JAMES ALLEN HUGGINS.
